Primary Examiner — John R Yeh(57) **CLAIM**

The ornamental design for a cleaning mop as shown and described.

DESCRIPTION

FIG. 1 is a top perspective view of a cleaning mop showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a bottom perspective view thereof;
FIG. 9 is an enlarged detail view taken from portion 9 of FIG. 1; and,
FIG. 10 is a top perspective view showing the separated state of cleaning mop base and main body.
The broken lines in the drawings depict portions of the cleaning mop that form no part of the claimed design.
